[57] CLAIM

The ornamental design for a novelty bath tub, as shown and described.

DESCRIPTION

FIG. 1 is a perspective view of a novelty bath tub showing our new design;

FIG. 2 is a top plan view thereof;

FIG. 3 is a front elevational view thereof;

FIG. 4 is a back elevational view thereof;

FIG. 5 is an end elevational view thereof; and,

FIG. 6 is an end elevational view of the opposite end.

Throughout the figures lines drawn in phantom are for illustrative purposes only and form no part of the claimed design.
